PLAN FILE

Charles B. Ulrich, Jamestown, N. Y.

Application January 22, 1940, Serial No. 314,957

10 Claims. (Cl. 129—16)

My invention pertains to vertical planfiles of the type intended to file and hold large plans, drawings, and other papers, as well as smaller papers of various kinds, in vertical arrangement in suspended and flexible pockets, suitable compression means being provided between the pockets to compress the contents thereof to hold said contents in vertical and compact condition in each pocket.

This invention provides an improved construction of such planfiles, by which in addition to the pockets being movable toward and from each other as heretofore, devices are provided in connection with the supporting rails of the planfile pockets, for grouping the pockets with a desired number of pockets in each group, which prevents undue expansion of certain of the pockets in a manner to prevent the effective use of others of the groups of pockets, and which provides that each of the pockets is immediately and effectively available to receive or deliver filed contents regardless of the condition of others of said pockets. The invention further provides an arrangement of supports for the cross-bars of the pockets coacting with compression mechanism between the pockets by which the sides of the pockets move nearly or quite into vertical positions by the weight in the pockets, which is the desired compression position of said pocket sides.

The invention will be best understood by reference to the accompanying drawings illustrating a preferred embodiment thereof in which—

Fig. 1 is a vertical, sectional view from front to rear through the planfile, taken along the line 1—1 in Fig. 2.

Fig. 2 is a vertical, sectional view of a part of the structure taken along the line 2—2 in Fig. 1.

Fig. 3 is a vertical, sectional view of a part of the structure to an enlarged scale taken along the line 3—3 in Fig. 1.

Fig. 4 is a view similar to Fig. 1 but to an enlarged scale, of a part of the lower ends of several adjacent pockets.

Fig. 5 is a vertical, sectional view of a part of the structure taken along the line 5—5 in Fig. 4.

Fig. 6 is a vertical, sectional view of a part of the structure taken along the line 6—6 in Fig. 3.

Fig. 7 is a horizontal, sectional view to an enlarged scale of a part of the structure taken along the line 7—7 in Figs. 1 and 3.

Fig. 8 shows in a view similar to Fig. 4 a modified construction of spacing devices for the bottoms of the pockets.

Fig. 9 is a bottom view of the parts shown in Fig. 8, and

Fig. 10 shows in a view similar to Fig. 1 but to an enlarged scale a portion of the upper portions of adjacent pockets after loading one of the pockets.

5 Similar numerals refer to similar parts as shown in the several views.

As shown in Fig. 1, the planfile consists of a casing 10 having a cover 11 and containing substantially parallel, horizontal pocket-supporting cross-bars 12 connected with and supporting the side walls 13 of the pockets, which side walls are preferably spaced strips of thin sheet metal connected at their lower ends with the flexible bottom members 14 of the pockets, which are preferably of suitable fabric. Resilient compression devices such as helico-spiral springs 15 are connected with and between the side walls of adjacent pockets to press the side walls of each pocket towards each other to compress the contents of the pocket and hold the same in vertical position. One side wall of each pocket has secured to its lower end portion, a plate 16 extending downwardly below the bottoms of the pockets to receive a retaining rod 17, adjacent ones of said plates being connected by spacing links 18 and 19. The retaining rod is preferably free from the casing and prevents the bottom of any pocket lifting above the bottoms of the other pockets, and the spacing links insure ample clearance space for the lower portion of each pocket between adjacent plates 16, so that each pocket is free to receive and discharge its contents.

The casing 10 is provided with inner and outer walls of sheet metal and the supporting structure of the planfile as well as the sides of the pockets are preferably of sheet metal, and on account of the small scale necessary in Figs. 1 and 2, the thickness of said sheet metal is shown by a single line.

40 As shown in Fig. 2 and more clearly in Fig. 3, one end of each cross-bar 12 is provided with a vertical slot 12a open at its lower end to receive and ride on a supporting rail 22 supported in the space between the inner and outer walls of the side of the casing 10, by angle members 22a formed from the channel member 22b forming a part of the side wall construction, and extending upwardly and having upwardly opening slots to receive and support the rail 22. Each cross-bar 12 has secured to it the upper ends of the corresponding pocket strips 13 to support the pockets of the planfile. As shown in Fig. 6, the cross-bars 12 are of rectangular cross-section and the pocket strips 13 are secured to them in any con-

venient manner, for example, by riveting as illustrated at 13a¹.

As shown in Figs. 4 and 5 the apertures in the plates 16 to receive the rod 17, are formed to also receive the ends of the spacing links 18 and 19, the links 18 being on one side and the links 19 on the other side of said rod. The links 18 and 19 are preferably made of suitable wire bent to the form shown. It will be understood that there are preferably several pairs of strips 13 to form the side walls of each pocket, depending upon the width of the planfile, and that each series of said strips 13 from front to rear of the planfile is preferably provided with a retaining rod 17 and spacing links 18 and 19 as described.

In the modified construction of lower spacing devices for the pockets, shown in Figs. 8 and 9, the pocket strips 13a are similar to the pocket strips 13, excepting that one strip 13a of each pocket is continued downwardly below the adjacent flexible pocket bottom 14a, and is provided at its lower end with tongues 13b extending through slots therefor in a spacing strip 24, the parts being held together by bending the tongues after they are passed through the strip 24. Each series of pocket strips 13a from front to rear of the planfile, is preferably provided with a spacing strip 24 where this construction is employed, and the lower portion of each pocket is thus provided with ample clearance space regardless of the extent of loading of the other pockets. The pockets in other respects may be constructed and may operate in substantially the same manner as the pockets described in connection with Figs. 1 and 4.

As shown in Fig. 7, the angle members 22a are so spaced as to receive a desired number of the cross-bars 12 between adjacent ones of them, thus grouping the pockets as desired, and said angle members limit the expansion of the pockets of any group to the space allotted to the group by the spacing of said angle members. Stop members 22c are formed from the member 22b to engage the ends of the rail 22 to restrain it from longitudinal movement. Between the cross-bars 12, springs 26 are disposed around the rail 22 which preferably is a cylindrical rod, the strength of the springs being sufficient to move the cross-bars 12 to positions spaced substantially equally from each other when the pockets are not loaded, but not sufficient to interfere with other spacings due to unequally loaded pockets, or to interfere with placing material in any pocket or removing the same therefrom. The other side of the casing is provided with a similar rail supporting and cross-bar spacing construction to support the pockets and afford the operation described, the pocket grouping construction being the same at each end of the cross-bars 12.

In the manner described, the invention provides a combined pocket-supporting and pocket-grouping construction contained in the side walls of the casing, so that no devices are required for the purpose inside of the upper portion of the casing, and the entire space in the casing is clear and unobstructed for use in connection with the filing pockets.

In Fig. 10 the action of the pocket supporting devices is illustrated. In placing a load 25 of papers or the like in one of the pockets, the cross-bars 12 supporting the pocket are pushed apart sufficiently to provide easy access to the pocket, having the cross-bars apart a corresponding amount on their rails 22. The weight

of the load 25 exerts a force vertically and downwardly on the pocket, which force may be represented by the arrow P. This force is divided between the pocket supporting strips 13 so that each strip supports its part of the load. On account of the separation of the cross-bars 12 referred to, the upper portions of the strips 13 of the loaded pocket are not vertical, because of the action of the upper compression springs 15, but are obliquely disposed and diverge upwardly. The portion of the vertical load 25 carried by each of the strips 13 supporting the load, therefore produces two component forces p and p1, each force p being in the direction of and sustained by the corresponding strip 13, and each force p1 being exerted horizontally and in a direction tending to move the load supporting cross-bars towards each other. In practice, the cross bars 12 readily separate against the action of the springs 26, to afford easy access to any pocket, and they also automatically move to positions substantially over the pocket strips due to the action of the forces p1 and to the action of the springs 26, when the operator releases the pocket supporting cross-bars, thus spacing the cross-bars substantially uniformly, depending of course on whether the pockets are uniformly loaded.

In the manner described, I provide means 30 within the side walls of the casing and associated with the pocket-supporting rails, for grouping the pockets in such a manner that each group is restricted to its allotted space in the casing, without interfering with the operation of any 35 pocket of any group, together with means tending to automatically effect uniform spacing of the pocket cross-bars when any opened pocket is released.

While I have shown my invention in the particular embodiments described, I do not limit myself thereto but include equivalents thereof within the scope of the appended claims.

What I claim is:

1. In a planfile, the combination of a casing 45 having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, and a horizontally disposed casing member in each of said sides of the casing and having integral angle members supporting the corresponding rail, said cross-bars being disposed in groups between said angle members.

2. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, and a horizontally disposed casing member in each of said sides of the casing and having integral angle members supporting the corresponding rail, said cross-bars being disposed in groups between said angle members, the upper edges of said angle members being slotted to form seats for said rails.

3. In a planfile, the combination of a casing having opposite sides each provided with spaced inner and outer walls, a rail horizontally supported in the space between the upper portions

of the walls of each of said sides, cross-bars horizontally supported by said rails for movement longitudinally of said rails, filing pockets suspended in said casing from said cross-bars, a horizontally disposed casing member in each of said sides of the casing and having integral angle members supporting the corresponding rail, said cross-bars being disposed in groups between said angle members, and springs between the end portions of said cross-bars and tending to space them from each other.

4. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, a horizontally disposed casing member in each of said sides of the casing and having integral angle members supporting the corresponding rail, said cross-bars being disposed in groups between said angle members, the upper edges of said angle members being slotted to form seats for said rails, said rails being cylindrical rods, and springs around said rails and between said cross-bars and tending to space said cross-bars from each other.

5. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, and a horizontally disposed casing member in each of said sides of the casing and having integral angle members supporting the corresponding rail, said cross-bars being disposed in groups between said angle members, each of said casing members also having integral angle members for engaging the ends of the corresponding rail and restraining the same from longitudinal movement.

6. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, and a horizontally disposed casing member in each of said sides of the casing and having integral angle members supporting the corresponding rail, said cross-bars being disposed in groups between said angle members, said cross-bars being of rectangular cross-section and having end slots opening through their lower edges for engagement with said rails.

7. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, and a horizontally disposed casing member in each of said sides of the casing and having in-

tegral angle members supporting the corresponding rail, said cross-bars being disposed in groups between said angle members, said cross-bars being of rectangular cross-section and having end slots opening through their lower edges for engagement with said rails, said casing having an inner vertical wall member extending over said cross-bars and restraining them from movement vertically from engagement with said rails.

8. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, and a horizontally disposed casing member in each of said sides of the casing and having integral angle members supporting the corresponding rail, said cross-bars being disposed in groups between said angle members, there being one of said integral angle members between each two adjacent groups of said cross-bars for each of said rails.

9. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, a horizontally disposed casing member in each of said sides of the casing and having integral angle members supporting the corresponding rail, said cross-bars being disposed in groups between said angle members, the upper edges of said angle members being slotted to form seats for said rails, said rails being cylindrical rods, and springs around said rails and between said cross-bars and tending to space said cross-bars from each other, each of said casing members also having integral angle members for engaging the ends of the corresponding rail and restraining the same from longitudinal movement.

10. In a planfile, the combination of a casing having opposite sides each provided with spaced inner and outer walls, a rail horizontally supported in the space between the upper portions of the walls of each of said sides, cross-bars horizontally supported by said rails for movement longitudinally of said rails, filing pockets suspended in said casing from said cross-bars, a horizontally disposed casing member in each of said sides of the casing and having integral angle members supporting the corresponding rail, said cross-bars being disposed in groups between said angle members, the upper edges of said angle members being slotted to form seats for said rails, said rails being cylindrical rods, and springs around said rails and between said cross-bars and tending to space said cross-bars from each other, each of said casing members also having integral angle members for engaging the ends of the corresponding rail and restraining the same from longitudinal movement, there being one of said integral angle members between each two adjacent groups of said cross-bars for each of said rails.

CHARLES B. ULRICH.
